(57) **CLAIM**

The ornamental design for an LED area light fixture, as shown and described.

DESCRIPTION

FIG. 1 is a bottom front perspective view of our new design; FIG. 2 is a top rear perspective view thereof; FIG. 3 is a bottom view thereof; FIG. 4 is a front view thereof; FIG. 5 is a right side profile view thereof, the left side profile being a mirror image thereof; FIG. 6 is a top view thereof; FIG. 7 is a rear view thereof; and, FIG. 8 is a second bottom front perspective showing additional environmental elements.

The views of the LED area light fixture not shown form no part of the claimed design. The dash-dot lines in FIGS. 1-8 immediately adjacent to the shaded area represent unclaimed boundaries of the design. The dash-dash lines elsewhere in FIGS. 1-8 refer to environmental elements only and form no part of the claimed design.
